UNITED STATES PATENT OFFICE.

WILLIAM H. LAMBERT, OF CHELSEA, MASSACHUSETTS.

FOOTWEAR.

1,303,565.

Specification of Letters Patent. Patented May 13, 1919.

Application filed May 25, 1918. Serial No. 236,482.

To all whom it may concern:

Be it known that I, WILLIAM H. LAMBERT, a subject of George V, King of England, residing at Chelsea, county of Suffolk, Commonwealth of Massachusetts, have invented certain new and useful Improvements in Footwear, of which the following is a specification.

This invention relates to articles fabricated from strands of fiber, and particularly to articles of foot wear formed from strands of Manila rope.

The provision of a suitable foot covering for sailors for wear on shipboard has been traditionally a difficult problem, of which the only satisfactory solution seemed to be to go barefoot. It is imperative that men on deck and at sea under all conditions of weather have a sure footing, upon which frequently, not only the performance of their duties, but even life and limb depends.

Conditions on board ship, whether of wooden construction or of steel, make the problem a varied one. Decks or other parts on which duties must be discharged are sometimes slippery, sometimes wet, sometimes extremely hot, and generally difficult for obtaining sure and comfortable footing. In times of greatest emergency, this footing is apt to be at its worst.

In general, the requirements are that foot wear prevent slipping, be easy and comfortable, be useful in or out of water, be undamaged by frequent wettings and dryings, afford reasonable protection against hot decks or other parts, and at the same time have suitable wearing qualities.

It is the object of my invention to provide a foot cover which shall to a very considerable extent fulfil all these requirements.

Briefly I carry out this part of my invention by forming a shoe of Manila fiber, the same being fabricated to the desired form by a system of hitching or knotting by which I am enabled to shape a suitable foot cover, which while extremely resistant to wear and cool and comfortable, is most practicable for exposure to frequent wettings and dryings, and is extremely efficient as a footing under the most trying conditions. In describing my invention, I shall discuss its embodiment particularly in the form of a shoe, although it will be understood that various forms of foot wear and other articles may be made.

In the drawings which form a part of this

application, I have shown such a shoe and have illustrated in a somewhat diagrammatical manner the making of the same.

Throughout the specification and drawings, like reference numerals are applied and indicate corresponding parts in the drawings.

Figure 1 is a diagrammatic side elevation of a shoe in accordance with my invention. 65

Fig. 2 is a similar view of a sole.

Fig. 3 is a similar indication of the toe construction, and

Fig. 4 an indication of a section of inter-hitched traverses before tightening. 70

In considering the form of my invention I have selected for the purposes of illustration, it is to be noted, first, that an anti-slipping tread is desired, and that a structure unaffected by frequent wettings and dryings is necessary. This matter of wetting and drying is not only important as regards the shoe itself, but as regards the foot of the wearer, that is to say, if the wearer has been standing with his feet in the water and then goes out on dry footing, it is desirable that his feet dry out as rapidly as possible.

It being practically impossible to make an article impervious, I have contemplated in my present invention a structure, which while not exactly open work as shown in the exaggerated illustration of Fig. 4, is still pervious, not only to water, but to air, so as to be practically ventilating, thus affording a quick drying, as well as giving a margin of come and go in case of shrinking and stretching.

As regards the material contemplated in my invention, I find that fiber, particularly the long fibers such as manila, jute, hemp and the like, have a very high wear resisting quality, at the same time being cheap and readily obtainable. I have also found, in the practice of my invention, that the strands of a rope made from such fiber afford a peculiarly adapted material on account of the twist of the strands, which persists even after unraveling. By selecting rope of suitable size and number of strands, a natural twist of the strand formed in the rope making can be secured having a proper relation to the size of the hitch or knot, so that in forming the hitches, the fiber is laid with a slight twist in each hitch, thus greatly strengthening the structure from hitch to hitch and traverse to traverse. I have indi-

cated this in Fig. 4 by lines 14 intended to indicate substantially a single twist to each hitch.

In considering my invention, it is necessary not only to understand the nature of the material and the unitary hitch, but also the matter of its practice.

Such a structure being extremely difficult of detail drawing, I have illustrated the same in my present drawing by a succession of straight parallel lines indicating the traverses, it being understood that each traverse is formed of a succession of individual hitches, each looped into or engaged in the loop between two adjacent hitches in a preceding traverse, as shown in Fig. 2. Each hitch may thus be said to consist of a portion of a strand and a loop.

As a specific illustration, in starting the sole of a shoe (see Fig. 2), the strand 1 is laid diagonally to form a line from the ball of the foot to the base of the little toe, which is the widest part of the sole. This is done in order that it will not be necessary to widen it but only to narrow.

The first traverse is laid with a succession of hitches or single knots in which the hitches of the second traverse are engaged, the bite of each hitch being taken through a loop of a hitch of the first traverse, the hitches being laid successively across and in a reverse direction in each succeeding traverse.

The traverse from 1 to 2 therefore, may be considered as the first; the traverse 2 to 3, the second; the traverse 3 to 4 the third traverse; 4 to 5 the fourth traverse, and so on narrowing toward the toe of the sole, the toe being preferably narrowed by a decrease in the number of hitches to a single last hitch which may be considered as the final traverse at the toe of the sole.

In a similar way, the free end of the first traverse of the sole may be brought back and hitched successively across its own rear, as from 1 to 6, then back, as from 6 to 7, and 7 to 8, and so on, narrowing toward the heel.

The upper of the shoe is preferably formed by starting at the last traverse of the toe, indicated at 9, and forming a succession of traverses, either from right to left, or left to right, back and forth across the toe and over the instep, preferably back to the waist of the foot, the last hitch of each traverse being taken through the adjacent edge hitch of the sole. It is to be understood that this method is being carried on over a suitable last of the desired size and configuration.

At the waist of the shoe it is usually desirable to fasten off the traverses which have become vertical or substantially vertical. In the case of a shoe, as distinguished from a slipper, the traverses after passing the

base of the instep may be divided, working back on two sides of the central division or front opening of the shoe.

These vertical traverses having been fastened off, a new series of horizontal traverses parallel to the sole is begun, the first engaging with the loops and the hitches on the edge of the sole to the vertical traverse on the other side, then back in reverse to the first traverse. I have indicated at 11 the beginnig of such a heel traverse, which runs around the foot to the other side, returning on itself in a traverse 12, being continued back again in a traverse 13, and so on, until the rear part of the shoe has been built up. This permits an easy shaping in of the shoe at the narrow part of the foot. In this way I am able to construct a well shaped shoe or other article.

The fiber is preferably worked in a damp condition, and may be slightly soaped or otherwise lubricated. The hitches may be formed by a machine, which however, forms no part of this application, it being entirely possible to form such structure with considerable rapidity by hand, employing merely a needle or bodkin, or other convenient instrument, sufficiently pointed to be thrust through loops of the hitches and carrying the end of the fiber strands.

While I have described a complete shoe made in accordance with my invention, including the sole, it will be understood that various parts of the shoe may be made of other material, and the shoe trimmed or eyeleted as desired, and an additional sole may be worked on where desired, or the shoe may be tapped.

The shoe which I have described is particularly adapted for service on shipboard. It is cheap and light and has great endurance, even with the roughest kind of usage, as the structure is very little affected by water, and not only dries out itself, but permits the foot of the wearer to dry out. On the hot decks of battleships, on gratings, grills and other parts, it affords a high degree of protection against heat, cold, roughness and slipperiness. It conforms to uneven foot holds and permits the foot to adapt itself to any position. Being substantially integral, it has no lines of fault or cleavage, and is readily repaired.

Various applications of my invention may be made, and a great variety of forms produced, and materials may be widely varied, all without parting from the spirit of my invention, if within the limits of the appended claims.

What I therefore claim and desire to secure by Letters Patent is:

1. As an article of manufacture, a shoe formed of fiber rope strands, said strands being laid in a plurality of successive traverses, the strand in each traverse being

formed in a succession of hitches and each hitch being taken through the loop of a hitch in a preceding traverse.

2. As a new article of manufacture, a shoe comprising a sole portion made up of a plurality of successive diagonal traverses, each traverse comprising a plurality of hitches, the hitches of each traverse being interknotted with those of the preceding traverse, and a fore part comprising a plurality of successive traverses or hitches laid transversely on the fore part of the foot and similarly successively interengaged, and a similar heel part vertically laid in successive similar engaged traverses of said hitches.

3. As a new article of manufacture, a shoe comprising a sole portion made up of a plurality of successive traverses, each traverse comprising a plurality of hitches, the hitches of each traverse being interknotted with those of the preceding traverse, and a fore part comprising a plurality of successive traverses of hitches laid on the fore part of the foot and similarly successively interengaged, and a similar heel part laid in successive similar engaged traverses of said hitches.

4. A shaped shoe formed of strands laid in a succession of contiguous traverses said traverses interknotted one with another at a plurality of points in such manner as to lock the formation against disintegration upon the severance of the strand in any traverse.

5. A shaped shoe formed of a single length of fibrous material laid in a continuous succession of traverses, each traverse interknotted with a preceding traverse at a plurality of points in such manner as to lock the formation against disintegration upon the severance of the strand in any traverse.

6. A shaped shoe formed of strands laid in a succession of contiguous traverses, each traverse interknotted with an adjacent traverse at a plurality of points in such man-

ner as to lock the formation against disintegration upon the severance of the strand in any traverse, and the knots providing a substantially continuous external wearing surface.

7. A shaped article of fabricated structure, comprising a plurality of courses of fibrous material laid in successive contiguous traverses, each traverse having a succession of individual loops and said loops engaged with the loops of an adjacent traverse in such manner as to lock the formation at a plurality of points against disintegration upon the severance of the strand in any traverse.

8. A fabricated shoe having a sole portion consisting of a plurality of successive traverses, each traverse comprising a plurality of hitches, and the hitches of each traverse encircling the strand of the preceding traverse and extending back and forth across the sole.

9. A fabricated shoe having a sole portion consisting of a plurality of successive inter-engaged traverses and having an upper formed of a succession of traverses extending back and forth across the toe and instep and hitched at their ends to the traverses of the sole.

10. A fabricated shoe upper consisting of a plurality of successive inter-engaged traverses, the traverses defining the toe and instep portion of the shoe extending back and forth between the margins of the shoe sole, and those defining the heel portion of the shoe extending from side to side of the shoe and parallel to the sole and being hitched to the traverses defining the instep portion.

In testimony whereof I affix my signature in presence of two witnesses.

WILLIAM H. LAMBERT.
